CLAIM

The ornamental design for a combined fountain pen and cap, as shown and described.

DESCRIPTION

FIG. 1 is a front elevational view of a combined fountain pen and cap showing our new design;

FIG. 2 is a left side elevational view, the right side being a mirror image thereof;

FIG. 3 is a left side elevational view with the cap member in a stored position, the right side being a mirror image thereof;

FIG. 4 is a top plan view of FIG. 2; and,

FIG. 5 is a bottom plan view of FIG. 3.
